MAGNETIC BALL TRANSFER

John A. Swenton, Bristol, Conn.

Application February 14, 1946, Serial No. 647,500

9 Claims. (Cl. 51—74)

1

This invention relates to a magnetic ball transfer, for grinding machines, such as ball or centerless grinding machines, designed to feed ball bearings one at a time automatically for grinding and to automatically discharge the same when the grinding operation is completed, so that all of the balls will have a standard size according to the size for which the machine is set.

Another object of the invention is to provide a magnetic ball transfer in which the balls are automatically fed for grinding and automatically discharged, the device being electrically and magnetically controlled to cause step feeding of the balls during the grinding operation so that they are automatically ground to a standard set size accurately and quickly and discharged as the grinding operation is completed.

Another object of the invention is to provide a novel and simple actuating mechanism for advancing or transferring the balls from feeding to the grinding and discharging positions and which will eliminate the complicated and expensive mechanism heretofore employed for transferring balls during such operations.

A still further object of the invention is to provide a reciprocating magnet which is automatically shifted to intermittently raise and release the balls during the grinding operation through a series of steps between grinding wheels and automatically shifted back and forth during the transferring operation by the automatic closing of circuits to the actuating mechanism energizing the magnets and de-energizing the same to release the balls after being picked up and transferred in the energized position of the magnet, and finally released for discharge into a pan or container, after being positioned and ground in the various grinding steps or positions of the device.

A still further object of the invention is to eliminate a major portion of the mechanism employed in connection with machines now generally in use, and which is capable of application to a centerless grinder for grinding ball bearings or the like in a simple and efficient manner, as well as accurately.

Other objects and advantages reside in the details of construction and operation as more fully hereinafter described and claimed, reference being had to the accompanying drawings forming part hereof, wherein like numerals refer to like parts throughout, and in which:

Figure 1 is a sectional elevation of a magnetic

ball transfer constructed in accordance with the invention.

Figure 2 is a vertical sectional view at right angles to Figure 1.

5 Figure 3 is a fragmentary sectional view showing the feeding arrangement for the balls.

Figure 4 is a fragmentary perspective view showing the ball holder for use during the grinding operation.

10 Figure 5 is a horizontal sectional elevation taken below the magnetic transfer, and

Figure 6 is a diagrammatic view showing the wiring arrangement for the contacts and switches.

15 Referring to the drawings in detail, in which like character references designate corresponding parts throughout the several views, the ball transfer device is applied to a grinding machine having a base 10 on which a trough or support

20 11 is provided having a holder 12 with a tapered upper portion having sockets 13 in which concave tapered pins 14 are mounted by means of their reduced shank portions 15. The grinding wheels 16 and 17 of different diameters, operate on opposite sides of the holder in the manner shown in Figure 2 of the drawings, and are adapted to grind the balls or ball bearings 18 shown mounted in the concaved upper end or seat of the holders or pins 14 so as to project peripherally therefrom. These grinding wheels 16 and 17 are arranged in spaced series driven by shafts 19 and 20 in any suitable manner in connection with the grinding machine. A ball transfer head 21 is provided and has its lower

25 30 portion tapered and similarly formed with concave recesses or grooves 22 concentrically curved at one side and having the other side toward the discharge end cut away as indicated at 23 to release the same more readily when the grinding operation is completed. A formed magnet

35 40 24 is provided by winding around the reciprocating transfer head 21 when the coil 24 is magnetized and is designed to operate in a recess 25 formed in the lower end of a holder 26 extending

45 30 transversely across the machine and having spindles 27 and 28 mounted on the ends thereof to operate in bearings or bushings 29 in uprights

31 mounted on the base 10. The electromagnetic ball transfer head or pick up plate or holder 21 is adapted to move up and down by means of vertical rods, bolts or pins 32 connected to the plate 21 and operating through sleeves or bushings 33 pressed into apertures vertically through the holder 26 and having their upper 50 ends connected by a horizontal cross bar 34

centrally provided with a bar 35 connected with a suitable mechanism 36 for raising and lowering the same, such as by means of a suitably actuated plunger. Springs 37 are disposed between the bar 34 and the holder 26 to normally elevate the plate 21 in the recess 25 in the holder 26 and cushion the downward movement thereof. A solenoid coil 38 is provided on the spindle or projecting end 28 and forms a solenoid at one end, designed to retract the holder 26 to the left, while movement in the opposite direction may be caused by a spring 39 connected to the end 27 of the holder 26 and to a bracket 40 mounted on the upright 30 tending to normally hold the reciprocating member 26 to the right in Figure 1 of the drawings.

A solenoid 41 is mounted on an upright or bearing 42 outwardly of the upright 31 and is connected at its core or armature 43 to a plunger 44 having a reduced lower portion and having an inclined passage 45 therethrough. A feed tube 46 is disposed in an opening 47 through the upright 42 in an inclined position, to feed the balls 18 down the same and normally checked by the plunger 44 until the magnet or solenoid 41 is energized to raise the plunger 44 and align the inclined passage 45 with the opening 47 to permit the balls to enter the latter one at a time and upon being lowered, to discharge through an inclined opening 48 leading into a discharge tube 49 for depositing the balls onto a cup 50 at the left hand end of the holder 12 and to enter one of the recesses 22 when the transfer plate 21 is magnetized and lowered so as to bodily raise the balls in a manner shown in Figure 1 and then release and deposit the same into pins or holders 14 upon the plate 21 and coil 24 being demagnetized with the transfer plate 21 lowered with holder 26, thus moving the balls step by step to the right for action upon the same by the series of grinding wheels 16 and 17, until they enter the last recess 22 for discharge into a cup 51 and discharge tube 52 to be deposited into a pan as ground. A spring 53 connects the lower reduced end of plunger 44 slidably in guide sleeve 54, to the bottom of the upright 31, and the plunger 44 is limited in its downward movement by engagement of the downwardly facing shoulder formed by the reduced lower end of the plunger 44 with a corresponding upwardly facing shoulder at the lower portion of the upright 42 at its enlarged portion, while permitting upward movement of the plunger 44.

It will be noted from Figure 2 that each end of the holder or plate 21 is provided with two of the guide rods or spindles 27 and 28 movable through the openings in the upright frame members 30 and 31, to maintain the device horizontally positioned and guide the same in its reciprocating movements. A lever 55 is pivoted at 56 to the holder at the plate 21 toward its left hand end and has a pair of contacts or arms 57 and 58 at its upper end spaced apart horizontally, co-acting with contacts 59 and 60 suitably supported above the bar 34 connected by the bolts or pins 32 to the plate 21 through the holder 26. The contacts 59 and 60 are connected to the line wires for a suitable source of energy indicated at 61 and 62 which are in turn connected to the solenoid coil 38 and solenoid 41 with an interposed control switch 63. A control switch 64 is also provided in the line 65 and connected to a bar lifting device or contact 65 adapted to engage a contact 66 mounted on and movable with the holder 26 so that when the latter is shifted to the right it will engage with contact 65 and close the circuit to the bar lifting de-

vice. Contacts 67 and 68 are provided on the holder 26 and the upright 30 respectively spaced apart when the holder 26 is moved to the left and adapted to engage when the holder 26 is moved to the right, to close the circuit to the solenoid coil 41. After each intermittent grinding operation, the magnet 21 is energized and raised to bodily raise the balls in the manner shown in Figure 1 of the drawings and move the same to the right to the dotted line position, after which the magnet 21 is de-energized at coil 24 to release the balls into the holders or cups formed by the pins 14 for another grinding operation, until the various steps shown as nine in number are completed and the balls are accurately ground and discharged into the cup 51 upon de-energization of the magnet 21 at the coil 24, for discharge into the outlet tube 52.

Thus, in the operation of the device, as the balls enter the feeding receptacle or cup 50 through the pipe 49, one at a time or singly, the ball transfer or plate 21 due to energization of the coil 24 formed thereon, is raised and picks up the ball when the lever 55 which is attached to the plate 21 and moves therewith, engages the copper contact 59. Due to the coil 24 receiving the current, the plate 21 is magnetized to form an electro-magnet, which attracts and raises the ball to hold it in the groove or recess 22 at that point over the cup 50. The magnet is guided in its upward movement by the bolts or rods 32 connected by the cross bar 34 as they slide up and down in the bushings 33 in the holder 26. When this takes place, the lever arm 58 is connected with the contact 60 to cause energization of the solenoid or magnet 38 after attracting the armature produced by the guide rod or spindle 28 and holding the ball transfer to the left. When the magnet moves upwardly in the holder to raise the ball therewith so as to clear the holders or pins 14 and the ribs in the grinding wheels, the arm 58 disengages from the contact 60, thus de-energizing the magnet 38 so that the spring 39 will move the holder to the right. This moves the ball transfer plate 21 to the right so as to position the balls over the next series of holders or pins 14, and so that the balls will be in line with the grooves of the wheels. A lever 65 is set to engage the contact 66 and trip the grinding switch which starts the mechanism when coming in contact with the bar 34 to which the ball transfer plate 21 is attached, thus lowering the same into the grinding position and releasing the balls into the holders or pins 14 upon de-energization of the coil 24 and electro-magnet formed by the plate 21. At this position, the lever 55 disengages the contact 59 de-magnetizing the coil 24 and releasing the balls to be dropped into the receptacle or cup 51. At this point, the lever arm engages the contact 60 to energize the solenoid 38 to pull the holder to the left together with the ball transfer plate 21, to the starting position.

By cutting the recesses or grooves 22 away at the right hand side, it lets the ball slide out of the groove into the ball transfer to release the same. In this way, the balls are lowered into the grinding position held by the holders or pins 14 in their concave upper ends. In this position, the lever 55 is set to slide onto the contact 59 when the balls are in the position between the holders or pins 14 or in the position intermediate that shown in Figure 1 of the drawings. At this time, the coil 24 is energized by the closing of the circuit therethrough, so as to again pick up the 75 balls being ground and allow a new one to be

picked up from the receptacle or cup 50. When the holder is to the right, actuated by the spring 39, the solenoid 41 is energized to raise the slide or plunger 44 and permit another ball to enter the opening 45, and upon de-energization of magnet 41 spring 53 lowers plunger 44 to opening 48 bringing it in line with the tube 49 and letting one ball enter or roll into the cup 50. When the holder slides back to the left pulled by the solenoid 38 against the action of the spring 39 upon energization of the coil or solenoid 38, the electro-magnetic member or solenoid 41 is de-energized and the spring 53 pulls the slide downwardly to release the ball. On the other hand, when the ball transfer and holder are at the starting position, the mechanism operated by the lever 65 and contact 66, being tripped by the lever to operate the bar lifting device of the usual grinding machine, is turned off, which allows the springs 37 to raise the bar 26 or holder formed thereby upwardly, taking the balls out of the grinding position and raising them high enough to clear the ribs of the wheels and cups or holders formed by the pins 14, so that they can be moved to line up with the next group of wheels and pins 14.

It will thus be seen that I have provided a magnetic ball transfer, which is very simple in construction and operation, and eliminates much of the complicated mechanism of the devices heretofore in use, while entirely automatically and magnetically operated. This is true as to the release as well as the raising and lowering of the balls during the grinding operation until the latter is accurately completed.

While in the foregoing there has been shown and described the preferred embodiment of this invention it is to be understood that minor changes in the details of construction, combination and arrangement of parts may be resorted to without departing from the spirit and scope of the invention as claimed.

What I claim is:

1. A magnetic ball transfer including a frame having uprights, a ball holder slidable horizontally therein and normally held in one position and movable to another position, means to move the holder to different positions, electro-magnetic means for holding the same in the other position, means electrically operated for automatically feeding balls singly to receiving position, an electro-magnet carried by said holder, means for raising and lowering said electro-magnet, means for receiving the balls in the different positions, said magnet having recesses cut out at one side to release the balls when shifted, means controlling said actuating means, and receiving means for the balls.

2. In a ball transfer and feeding device for a centerless grinder for grinding ball bearings or the like, a frame, a holder reciprocable horizontally of the frame, a magnetic plate movable vertically in the holder and normally held in an elevated position, said plate having a plurality of spaced ball receiving recesses, at its lower end a ball holder mounted beneath the recesses, a plunger movable vertically and normally held in a lowered position, said plunger having a ball receiving opening, means for feeding balls singularly to said opening when the plunger is elevated, a ball receiving cup mounted beneath the first ball receiving recess, a passage leading from the opening when in a lowered position to convey the balls to the cup singly, magnetic means intermittently operated to elevate the plunger for

receiving a ball and to discharge same upon demagnetization thereof and return to a lowered position, means magnetically operated to move the holder and plate in a direction opposed to the feeding direction, in position to engage and lift the ball from the cup magnetically when lowered, means to move the holder and plate in the opposite direction when raised, to feed the balls step-by-step from the cup to the successive holding means under the recesses in the plate, control means automatically connecting said magnetic means in timed relation with a source of electrical energy to advance the balls into successive grinding positions in the holders below the recesses and to discharge the balls from the end recess at the end opposite the cup after operations thereon by the grinding wheels of the grinding machine, and means for receiving and discharging the ground balls.

3. A magnetic ball transfer for grinding machines having opposed series of grinding wheels adapted for grinding action upon the balls therebetween in grinding positions, including a frame, a holder movable in the frame, magnetic means carried by said holder, means for intermittently raising and lowering the magnetic means, ball receiving means, means for singly feeding the balls to the receiving means, means for holding the balls in grinding positions, said magnetic means adapted to engage and bodily raise the balls from the receiving means and the holding means after being ground by the wheels and to move the same progressively along the holding means and series of grinding wheels to different grinding positions therebetween and to release the same to the next holders upon being lowered and de-magnetized, and means for automatically actuating said feeding means, raising and lowering means for the magnetic means and moving the latter to receiving and releasing positions and for magnetizing and de-magnetizing said magnetic means in sequence.

4. A magnetic ball transfer for grinding machines having opposed rows of grinding wheels defining grinding positions therebetween, including a frame having uprights, ball holding means between the wheels, means for intermittently feeding the balls singly to the holding means, means movable in the uprights for bodily lifting the balls from the holding means and intermittently moving the same progressively across the holding means, means for lowering said lifting and moving means at each end of its movement, means for releasing the balls therefrom when moved, and means for discharging the balls upon completion of the grinding action thereon after passing the last grinding wheels and being raised from the holding means therebetween.

5. The combination with a grinding machine having opposed rows of grinding wheels defining grinding positions therebetween, a magnetic ball transfer including a frame having uprights, a holder movable in said uprights, means for firmly holding the holder to one side, ball receiving seats between the rows of grinding wheels for receiving the balls in grinding position, means to singly feed the balls to the seats, magnetic means to move the holder to the other side against the action of the first named means, magnetic means for energizing said holder, means for raising and lowering said magnetic holder means to engage and raise the balls when moved to the other side and lowered for moving the same to one side when said last named magnetic means is de-energized and for progressively advancing the various

balls across the rows of grinding wheels to successive grinding positions, means to lower the holder for depositing the balls upon the seats progressively across the rows, for action thereon by the grinding wheels, discharge means for the balls upon lowering of the holder means and de-energization thereof, and means automatically controlling said feeding, raising and release means.

6. The combination with a grinding machine having a series of opposed rows of grinding wheels defining grinding positions therebetween, a magnetic ball transfer including a frame having uprights, a holder movable therein, means firmly holding the holder to one side, magnetic means to move the holder to the other side against the action of the first named means, magnetic means for energizing said holder, means for raising and lowering said magnetic holder means, means for automatically feeding the balls singly, a receiving member for receiving said balls, means for progressively raising and moving the balls progressively across the various grinding wheels to grinding positions therebetween and for progressively advancing the same across the grinding positions, seats for holding the balls in said grinding positions, means for discharging the balls upon the lowering thereof with the holder means and de-energization thereof, and means for automatically controlling said feeding, raising and release means.

7. In a ball transfer and feeding device for a grinder for grinding ball bearings or the like, a frame, a holder reciprocable horizontally of the frame, a magnetic plate movable vertically in the holder, said plate having a plurality of spaced ball receiving recesses at its lower end, ball holders mounted beneath the recesses, means for feeding balls singly, a ball receiving cup mounted beneath the first ball receiving recess, means to intermittently lower the magnetic plate to engage and lift a ball from the cup, means to move the holder and plate in a direction opposed to the feeding direction for engagement with the ball, means to move the holder and plate in the feeding direction across the grinding wheels to successive grinding positions, seats between the respective opposed grinding wheels in the grinding positions to hold the balls while being ground, said balls being fed step by step from the cup to successive recesses

and grinding positions and means to discharge the balls from the end recess at the end opposite the cup after operation thereon by the grinding wheels of the grinding machine.

- 5 8. A magnetic ball transfer for grinding machines having opposed grinding wheels defining a grinding position therebetween, including means for holding the balls in grinding position, a receptacle for receiving balls to be ground, means 10 for feeding the balls singly to the receptacle, means for magnetically raising the balls from the receptacle and from grinding position, means for moving said magnetic means to advance the position of the balls from the receptacle to the holding means in grinding position and from the holding means in grinding position to a discharge position beyond the holding means, and means for releasing the balls from the magnetic means when moved to an advanced position above the holding means and to a discharge position.
- 20 9. A magnetic ball transfer for grinding machines having opposed series of grinding wheels between which the balls are adapted to be held in grinding positions, including means for holding the balls in grinding positions, a receptacle for receiving the balls to be ground, means for feeding the balls singly to the receptacle, means for magnetically raising the balls bodily from the receptacle and from the grinding positions, means 25 for moving said magnetic means to advance the position of the balls from the receptacle to the holding means and simultaneously from the holding means to successive holding means and beyond the latter for discharge intermittently in the raised positions, means for releasing the balls 30 when advanced, and means for returning said raising means to its initial position.
